UNITED STATES PATENT OFFICE.

JAMES HEWETT, OF CLINTON, MASSACHUSETTS, ASSIGNOR TO HIMSELF AND THOMAS ELLIOTT, OF SAME PLACE.

IMPROVED SKATE-FASTENING.

Specification forming part of Letters Patent No. 40,211, dated October 6, 1863.

To all whom it may concern:

Be it known that I, JAMES HEWETT, of Clinton, in the county of Worcester and State of Massachusetts, have invented a new and Improved Skate-Fastening; and I do hereby declare that the following is a full, clear, and exact description of the same, reference being had to the accompanying drawings, making a part of this specification, in which—

Figure 1 is a side sectional view of my invention, taken in the line $x x$, Fig. 2; Fig. 2, a plan or top view of the same; Fig. 3, a perspective view of the same in an open state.

Similar letters of reference indicate corresponding parts in the several figures.

This invention consists in a clamp for securing the skate to the heel of the boot or shoe, the parts being so arranged that the skate, in being adjusted or secured to the boot or shoe, is made to serve as a lever, so as to render the adjustment extremely easy, the clamp at the same time firmly securing the skate to the heel, and in such a manner as to cause the heel to be grasped firmer as it is raised up from the ice in skating, and at the same time tendency to prevent the skate moving laterally before the toe-strap is fastened over the front part of the boot or shoe.

To enable those skilled in the art to fully understand and construct my invention, I will proceed to describe it.

A represents a wire or rod, which is bent or curved in bow form, and passes through a lug or projection, a, on a strap, B, which is screwed to the back end of the stock or foot-stand of the skate.

C represents a heel-bearing, which is provided with an ear or lug, b, at each end, between which the projection a is fitted, and through which and the ears b b a pin, c, passes. This heel-bearing is allowed to work freely on the pin c, and its front part, d, which is the part that connects the ears b b, is provided with spurs or plates e, to catch into the back of the heel of the boot or shoe. The lower end of the heel-bearing is provided with a projecting plate, f, which, when the skate is adjusted to the boot or shoe, fits in a recess, g,

in the strap B. The ends of the wire or rod A have screw-threads h cut on them, on each of which a bar, i, is screwed. These bars i i lap over each other at their inner ends, and are connected by a screw, j, which passes through an oblong slot, k, in one of the bars and into a female screw-thread in the other bar. The bars i i are adjusted on the wire or rod A, so that the heel of the boot or shoe may fit properly within the wire or rod A, the bars i i being at the front side of the heel, as shown in Fig. 1.

In adjusting the skate to the heel of the boot or shoe the skate hangs in about a vertical position, and the heel is inserted within the wire or rod A, the back part of the heel being in contact with the bearing D and resting on the projecting plate f. The skate is then turned upward in contact with the sole of the boot or shoe, and the heel is clamped firmly between the bars i i and the bearing D. The inner sides of the bars i are corrugated, as shown at i', to prevent them from slipping.

This invention may be applied at a small cost to the ordinary skates in use, and it firmly connects the back part of the skate to the boot or shoe, and possesses the advantage of being readily applied to the heel of the boot or shoe and causing the heel to be clamped the firmer or more strongly as it is raised from the ice, thereby obviating the difficulty, frequent in other fastenings, of the heel becoming loose from that cause.

Having thus described my invention, what I claim as new, and desire to secure by Letters Patent, is—

The curved wire or rod A, fitted in the lug or projection a of the strap B, in combination with the swinging heel-bearing D, attached to the lug or projection a, and the bars i i, fitted on the ends of the wire or rod A, all being arranged substantially as and for the purpose herein set forth.

JAMES HEWETT.
